UNITED STATES PATENT OFFICE.

WOLF CAHN AND PHILIP H. LONG, OF NEWARK, NEW JERSEY, ASSIGNEES
TO THE LONG AND KOCH COMPANY, OF NEWARK, NEW JERSEY, A
CORPORATION OF NEW JERSEY.

CLASP.

SPECIFICATION forming part of Letters Patent No. 769,336, dated September 6, 1904.

Application filed April 11, 1904. Serial No. 202,482. (No model.)

To all whom it may concern:

Be it known that we, WOLF CAHN and PHILIP H. LONG, citizens of the United States, and residents of Newark, in the county of 5 Essex and State of New Jersey, have made and invented certain new and useful Improvements in Clasps, of which the following is a specification.

Our invention relates to an improvement 10 in clasps, and more particularly to that kind or style thereof usually known and referred to as "necktie" clasps or fasteners employed for the purpose of securing the tie to the shirt-bosom, the object of our invention being 15 to produce an article of this kind or character which shall be simple in construction, effective in use, and which at the same time shall be cheaper to manufacture than those commonly employed for the same purpose.

With these and other ends in view our invention consists in certain novel features of 20 construction and combinations of parts, as will be hereinafter fully described, and pointed out in the claim.

In the accompanying drawings, Figure 1 is 25 a view in side elevation of our improved clasp, the same being shown in its closed adjustment. Fig. 2 is a longitudinal sectional view of the same, the clasp being shown in its open 30 adjustment. Fig. 3 is a vertical sectional view taken on the line 3-3 of Fig. 2 looking in the direction as indicated by the arrow. Fig. 4 is a view in side elevation of the upper plate detached. Fig. 5 is a top plan view of the 35 lower or spring plate.

As shown by the drawings, the clasp consists of but two parts—namely, the upper or top plate A and the lower or spring plate B, the forward end of said upper plate A being 40 provided with the downwardly-projecting teeth *a* and its sides with the ears *b*, said ears having formed therein an opening *c* of the shape shown—that is, of somewhat the shape of a heart—the point *d* acting as a pivot or bearing for the lower or spring plate B in opening or closing the clasp, as hereinafter described. The lower or spring plate B has also formed on its forward end teeth *e*, which

when the parts are properly assembled and the clasp closed mesh with the teeth *a*, as 50 shown in Fig. 1, the sides of the plate being provided with the lugs *h*, adapted to pass through the openings *c* in the ears *b*, the extreme ends of said lugs being bent downwardly in order to prevent the two plates 55 from becoming disengaged.

The central portion of the plate B is slit and bent upwardly to form the spring-finger C, one end of the finger remaining integral with the plate and the opposite end bearing 60 against the under side of the plate A behind the ears *b*, the tendency of the spring being to retain the forward ends of the plates in contact, as shown in Fig. 1, or, in other words, to retain the clasp in its closed adjustment. 65 If pressure, however, is exerted upon the rear ends of the plates, the forward ends thereof will open or separate, as illustrated in Fig. 2, the lugs *h* rocking upon the bearing points or pivots *d*, the curved portion of the spring-finger C being slightly forced down through the central opening *i* of the plate B. When the pressure is released, the tension of the spring-finger C will immediately separate the rear ends of the plates A and B and close the 70 forward ends, the teeth *a* *e* being brought into mesh, as before described.

In order to sufficiently stiffen and strengthen the plate B, and especially the rear end thereof, we provide the same with the rib *k*, extending 80 entirely around the plate, parallel with the outer edge thereof, it having been shown in practice that unless the plate is so formed it is liable to bend in opening the clasp against the tension of the spring-finger C. 85

It will be understood from the foregoing that the clasp is simple and economical to construct, and consisting, as it does, of but two pieces or parts the latter are easily and readily assembled.

Having fully described our invention, what we claim as new, and desire to secure by Letters Patent, is—

A clasp consisting of two plates one of which is provided with teeth on its forward end and ears depending from the sides thereof, each

of said ears having formed therein a slot into which extends a portion of the metal forming a pivot, the other of said plates being also provided with teeth meshing with said former 5 teeth, and with lugs on said sides, the latter passing through said ears and bearing on said pivots, the central portion of said second plate being formed into a spring, the free end thereof bearing against the under side of the 10 first-mentioned plate and retaining the clasp

in its closed adjustment, substantially as described.

Signed at Newark, in the county of Essex and State of New Jersey, this 8th day of April, A. D. 1904.

WOLF CAHN.
PHILIP H. LONG.
